SHAMPOO CHAIR

Flora H. Ellinger, Chicago, Ill.

Application December 19, 1942, Serial No. 469,523

12 Claims. (Cl. 4—159)

The present invention relates in general to improvements in apparatus for facilitating the treatment of human hair, and relates more specifically to various improvements in the construction and operation of a combined sink and seat or shampoo chair of the general type disclosed in my Patent No. 2,315,153, granted March 30, 1943.

An object of the present invention is to provide an improved shampoo chair assemblage which is simple and compact in construction, and which is moreover highly efficient and flexible in use.

In my prior patent above identified, is shown an improved shampoo chair comprising a unitary wash basin and seat having an integral neck engaging saddle near the upper rear portion of the seat, and also having drainage portions on opposite sides of the seat and saddle directed toward the outlet portion of the basin. This prior unitary chair and sink also has liquid supply and drainage fittings associated with the wash basin, and while my prior assemblage or shampoo unit is extremely useful and greatly facilitates shampooing or other treatment of hair as compared to previous cumbersome and unsanitary methods, it was not sufficiently flexible in its adaptations to meet various operating conditions. In the prior structure the neck engaging saddle was upwardly directed and was also approximately vertically adjustable so as to accommodate both tall and short persons, and the unit was also devoid of suitable supporting and drainage devices upon which long hair could rest while being treated, without dipping into the wash basin. It has now been found that the accommodation of short and tall individuals can be more readily effected by disposing the neck saddle approximately horizontally and by adjusting the seat within the seating recess so that various sized persons will most effectively and comfortably contact with the neck receiving indentation of the saddle. I have also discovered that by providing suitable drain boards integral with the sink and flaring laterally and rearwardly away from the saddle, the hair can be more thoroughly washed and rinsed without coming in contact with polluted liquid.

It is therefore a more specific object of my present invention to provide various improvements in the details of construction and operation of such shampoo units, whereby the efficiency and adaptations thereof are materially improved, while simplification in construction also results.

Another specific object of this invention is to provide a combined hair treating basin and occupant seat of improved appearance, and which may be more readily manipulated by an operator.

A further specific object of the invention is to provide an improved shampoo chair and sink

assembly which is portable and readily accessible from all directions, and which is relatively compact in structure.

Still another specific object of my invention is to provide an extremely useful accessory for beauty parlors, barber shops or the like, which is also relatively attractive and highly effective in use.

These and other specific objects and advantages of the invention will be apparent from the following detailed description.

A clear conception of the several improved features constituting my present invention, and of the construction and operation of shampoo chairs built in accordance therewith, may be had by referring to the drawings accompanying and forming a part of this specification wherein like reference characters designate the same or similar parts in the various views.

Fig. 1 is a front elevation of one of the improved shampoo units, a portion of the chair having been broken away to reveal normally concealed internal structure.

Fig. 2 is a full top view of the improved shampoo unit of Fig. 1.

Fig. 3 is a part sectional side view of the improved shampoo chair, the section having been taken vertically and centrally through the wash basin and neck engaging saddle; and

Fig. 4 is a part sectional top view of the shampoo apparatus showing normally concealed internal structure and one of the doors for permitting access to the cabinet.

While the invention has been shown and described as being especially applicable to portable shampoo chairs each comprising a wash basin and adjustable seat structure formed integral therewith, it is not my desire or intent to thereby necessarily limit the scope, or the utility of the several improved features.

Referring to the drawings, the improved portable shampoo unit shown therein comprises in general, a sink or wash basin 7 permanently secured to a frame or cabinet 6 and being provided with water supply fixtures 8, 9 and with a waste liquid drainage fixture 10; a seating recess 11 formed integral with the basin supporting cabinet 6 and having therein a movable seat or chair 12; an approximately horizontal neck engaging detent or saddle 13 rigidly associated with the basin 7 near the upper rear portion of the seating recess 11 and extending rearwardly into the basin 7 so as to provide forwardly extending drainage portions 14 on opposite sides of the saddle 13; a relatively extensive drain board or apron 15 formed integral with the basin 7 and flaring laterally and rearwardly away from the saddle 13 above the basin bottom; and a slidable support 16 and a hydraulic jack 17 mounted within the seating recess 11 and cooperating with the chair

12 to effect both horizontal and vertical adjustment thereof relative to the basin 7 and saddle 13.

The cabinet 6 which supports the basin 7 and neck saddle 13, and in which the seating recess 11 is formed, may be mounted upon castors or gliders, not shown, so as to permit ready shifting of the unit about a room; and the rear portion of the cabinet 6 is preferably provided with doors 18 for permitting ready access to the concealed portions of the plumbing, and to storage shelving 19 disposed within the cabinet beneath the basin 7. While the fresh liquid supply faucet 8 is fixedly mounted relative to the basin 7, the rinsing spray head 9 is preferably connected to the supply pipe 20 by a flexible hose, not shown, so that the head 9 may be brought into close proximity with the head of a person occupying the chair 12; and the liquid supply fixtures 8, 9 should also be provided with the usual hot and cold water control and diverter valves. The drain fitting 10 may be of 25 relatively conventional design provided with the usual trap; and when the unit is intended for portable use, the supply and waste pipes should be connected to the liquid sources and with the sewer by means of flexible conduits in an obvious manner.

The drainage basin 7, cabinet 6, and the walls of the seating recess 11 may all be formed of suitable sheet material, and the drain board 15 is preferably formed integral with the basin 7, while the neck engaging saddle 13 may be lined with padding of sponge rubber or the like for increased comfort. The horizontal saddle 13 should also be relatively deep and smoothly curved and rounded to eliminate annoying corners; and since this saddle 13 is fixedly located with respect to the cabinet 6 and basin 7, the chair 12 which is mounted within the recess 11 should be provided with mechanism for effecting adjustment of the seat so as to cause the saddle 13 to properly coact with persons of different sizes. For this purpose, the recess 11 is provided with horizontal rails or supports 16 along which the base 21 of the chair 12 is slideable back and forth so as to move the chair bodily toward and away from the basin 7 and saddle 13; and the combined seat and back of the chair 12, is independently vertically movable within the recess 11 by means of the hydraulic lift or jack 17, the cylinder of which is mounted upon the base 21, and the movable plunger of which coacts with the bottom of the seat.

The hydraulic jack 17 may be supplied with liquid under pressure from any suitable source and its operation is controllable by means of an actuating lever 22 shown in Figs. 1 and 2, and this jack is adapted to lift the chair 12 bodily to any position between the low and high limiting positions illustrated in solid and dot-and-dash lines respectively, in Fig. 3. While the seat or chair 12 has been shown as being rigidly mounted upon the ram of the hydraulic jack 17, this seat may also be tiltably secured to this ram as in the ordinary barber's chair, so that the back of the chair may also be inclined at different angles relative to the saddle 13. The pressure and release mechanisms for effecting actuation of the hoist are of well known construction and may be housed within the cabinet 6; and in order to properly vertically guide the chair 12, the cabinet 6 may be provided with guide rails 23 coacting with slides 24 carried by the chair 12. With this assemblage and construction of the elements, the chair 12 may obviously be readily adjusted both horizontally and vertically relative to the basin 7 and saddle 13; and the entire compact assemblage

may be attractively constructed and decorated so as to provide a pleasing appearance.

While the improved chair and wash basin assemblage is especially adapted for advantageous use when shampooing the hair of individuals occupying the seat, it may also be used for diverse purposes such as cutting and otherwise treating the hair, and is therefore adapted for use in barber shops as well as in beauty parlors. During normal use of the improved shampoo unit, the occupant will be seated upon the chair 12 and the operator will then adjust the location of the chair 12 so as to cause the saddle 13 to effectively and comfortably engage the occupant's neck. The operator is then free to advance to any position about the basin 7 and to manipulate the water supply fixtures 8, 9, and the drain board 15 and forwardly projecting basin portions 14 will most effectively conduct drainage liquid toward the basin drain 10 from which the waste liquid will be conducted to the sewer. The extensive drain board 15 which is disposed above the bottom of the basin 7 will obviously permit long hair to be spread out both laterally and rearwardly so as to permit most effective treatment thereof and without permitting the hair to extend into the bottom of the basin where it might contact waste liquid. The seat 12 can obviously be quickly and readily adjusted by the operator so as to accommodate persons of different sizes, and the saddle 13 will comfortably engage the necks of these persons because of the padding provided thereon and the smooth formation thereof.

From the foregoing detailed description it will be apparent that my present invention provides an improved shampoo chair or the like which is extremely simple and compact in construction and which is also highly efficient in use and flexible in its adaptations. The horizontal disposition of the neck engaging saddle and the adjustability of the chair 12 make the assemblage adaptable for diverse uses without causing portions to project above the top of the basin 7, and the entire unit may obviously be shifted to any desired location by virtue of the fact that the chair is united directly with the washing or treating basin 7. In cases where the chair 12 is also provided with tilting mechanism as in the ordinary hydraulic barber's chair, the improved assemblage may also be utilized for facial treatments and shaving purposes, and the saddle 13 may then be employed as a head rest. While some of the connections and actuating mechanisms have been omitted from the present disclosure for the sake of clearness, the construction of these mechanisms and connections is well known in the art and their inclusion would merely complicate the present disclosure. The provision of the shelving 19 and doors 18 will permit storage of diverse articles within the cabinet 6, and will also facilitate access to the concealed portions of the plumbing. The assemblage can be manufactured and sold at moderate cost and presents an exceedingly neat and finished appearance.

It should be understood that it is not desired to limit this invention to the exact details of construction, or to the precise mode of use, herein shown and described, for various modifications within the scope of the claims may occur to persons skilled in the art.

I claim:

1. A shampoo chair, comprising, a wash basin provided with an integral forwardly extending lower frame portion having therein a seating re-

cess and with a forwardly open neck engaging saddle adjoining the basin near the upper rear portion of the seating recess, and a seat adjustable upon said frame within said recess relative to said saddle.

2. A shampoo chair, comprising, a wash basin provided with an integral forwardly extending lower frame portion having therein a seating recess and with a forwardly open neck engaging saddle adjoining the basin near the upper rear portion of the seating recess, said basin having rearwardly directed drainage portions extending along the opposite sides of said saddle, and a seat adjustable upon said frame portion within said recess relative to said saddle.

3. A shampoo chair, comprising, a wash basin provided with an integral forwardly extending lower guiding portion having therein a seating recess and with a forwardly open neck engaging saddle adjoining the basin near the upper rear portion of the seating recess, and a seat adjustable along said guiding portion within said recess toward and away from said saddle.

4. A shampoo chair, comprising, a wash basin provided with an integral forwardly extending lower supporting portion having therein a seating recess and with a forwardly open neck engaging saddle adjoining the top of the basin near the upper rear portion of the seating recess, said basin having rearwardly directed drainage portions extending along the opposite sides of said saddle and away from said recess, and a seat adjustable in elevation upon said supporting portion within said recess and relative to said saddle.

5. A shampoo chair, comprising, a wash basin having liquid supply fixtures associated therewith and being provided with an integral forwardly extending lower frame portion having therein a seating recess and with an approximately horizontal forwardly open neck engaging saddle adjoining the basin near the upper rear portion of the seating recess, said basin also having integral rearwardly directed and open drainage portions extending along the sides of said saddle and away from said recess, a seat adjustably mounted upon said frame within said recess, and means for adjusting said seat relative to said saddle.

6. A shampoo chair, comprising, a wash basin having liquid supply and drainage fixtures associated therewith and being provided with an integral forwardly extending lower frame portion having therein a seating recess and with an integral approximately horizontal forwardly open neck engaging saddle adjoining the basin near the upper rear portion of the seating recess, and a seat adjustably mounted upon said frame within said recess.

7. A shampoo chair, comprising, a wash basin having liquid supply and drainage fixtures associated therewith and being provided with an integral forwardly extending lower guiding and supporting portion having therein a seating recess and with an integral approximately horizontal forwardly open neck engaging saddle adjoining the basin near the upper rear portion of the seating recess, a seat adjustably mounted upon said guiding and supporting portion within said recess, and means for effecting adjustment of said seat relative to said saddle.

8. A shampoo chair, comprising, a wash basin having liquid supply and drainage fittings asso-

ciated therewith and being provided with an integral forwardly extending lower guiding portion having therein a seating recess and with an integral approximately horizontal forwardly open neck engaging saddle adjoining the basin near the upper rear portion of the seating recess, said basin also having integral rearwardly open drainage depressions extending along the sides of the saddle toward the drainage fitting and with an integral drain board directed laterally and rearwardly away from said saddle, and a seat slidably adjustable along said guiding portion toward and away from said saddle and drain board.

9. A shampoo chair, comprising, a wash basin having liquid supply and drainage fittings associated therewith and being provided with an integral forwardly extending lower frame portion having therein a seating recess and with an integral approximately horizontal forwardly open neck engaging saddle adjoining the basin near the upper rear portion of the seating recess, said basin also having integral rearwardly open drainage depressions extending along the sides of the saddle toward the drainage fitting and with an integral drain board directed laterally and rearwardly away from said saddle, and a seat adjustably mounted upon said frame portion within said recess.

10. A shampoo chair, comprising, a wash basin having liquid supply and drainage fittings associated therewith and being provided with an integral forwardly extending lower guiding and supporting portion having therein a seating recess and with an integral approximately horizontal forwardly open neck engaging saddle adjoining the basin near the upper rear portion of the seating recess, said basin also having integral rearwardly directed and open drainage depressions extending along the sides of the saddle toward the drainage fitting and with an integral drain board directed laterally and rearwardly away from said saddle between said depressions, a seat mounted within said recess, and means for effecting definite adjustment of said seat both horizontally and vertically within the recess and relative to said guiding and supporting portion.

11. A unitary portable shampoo chair, comprising, a wash basin provided with an integral forwardly open neck engaging saddle at the front edge thereof and also being provided with a forwardly extending lower frame portion having therein a forwardly open seating recess disposed beneath the saddle, guide ways mounted upon said frame portion and extending away from said basin, and a seat slidably adjustable upon said frame within said recess and along said guide ways.

12. A unitary portable shampoo chair, comprising, a wash basin provided with an integral forwardly open neck engaging saddle at the front edge thereof and also being provided with a forwardly extending lower frame portion having therein a forwardly open seating recess disposed beneath the saddle, guide ways mounted upon said frame portion and extending away from said basin, a seat slidably adjustable upon said frame within said recess and along said guide ways, and means for also effecting vertical adjustment of said seat within said recess toward and away from said saddle.
